UNITED STATES PATENT OFFICE.

JAMES HOLLINGSWORTH, OF CHICAGO, ILLINOIS, ASSIGNOR TO HOLLINGSWORTH & COUGHLIN, OF SAME PLACE.

APPARATUS FOR MOVING HOUSES.

SPECIFICATION forming part of Letters Patent No. 295,921, dated April 1, 1884.

Application filed October 1, 1883. (No model.)

To all whom it may concern:

Be it known that I, JAMES HOLLINGSWORTH, a citizen of the United States, residing in Chicago, in the county of Cook and State of Illinois, have invented a new and useful Improvement in Apparatus for Moving Houses, of which the following is a specification.

In the operation of moving heavy brick or stone buildings, the capstan which is so commonly used in the moving of light buildings is impracticable, often because room for the capstan and the sweep required for the horse actuating it cannot be had, and more often because a capstan cannot without great difficulty be secured with sufficient firmness to hold it against the power it is capable of exerting upon the building, and hence it has become customary to push such weighty buildings upon either rollers or slideways by means of jack-screws planted against objects of resistance secured in the ground.

To obviate some of the difficulties attending the latter mode is the object of the present invention, the nature whereof will be fully understood from the following description and the accompanying drawings.

In said drawings, Figure 1 is a side elevation of a building being moved by my improved apparatus. Fig. 2 is a plan of the invention. Fig. 3 is an enlarged detail elevation of one of the screws; and Fig. 4 is a like detail, showing a plan of the slide-timbers.

In the drawings, A represents the crib-work or pile of timbers by which the building B is supported and upon which it is being moved.

C C represent lines of timbers joined together at their abutting ends by side strap-plates, c, and bolts c', and forming the slideways or runways, as the case may be, whereon the building slides or rolls. The ways C C are used in such number as the necessities of the case may require, and are prolonged to the point to which the building is to be moved by transferring the length forming them from the rear to the front as the building progresses toward its destination.

D D are the slide-boards, which slide upon the ways C when no rollers are used. They are smooth-surfaced and greased, as are also the ways C, in the usual manner.

Between the boards D and the building are customarily placed the needle-beams E, the sill F, and the transverse timbers G. The motive force is applied to the sill-timbers F by screws, each having a center boss, h, by means of which it is operated, and a right-threaded portion, h¹, at one side of the boss and a left-threaded portion, h², at the other side thereof. These threaded portions work in nuts i, inserted in the ends of timber-pieces I, which are bored out longitudinally to give entrance to the screw. The resistance against which the screws work is afforded by anchor-blocks J, which are secured to the slideways by metal straps j, taking hold of the ends of pins 65 j', passing through the slideways at openings j''. As the building rests immediately or proximately upon the same timbers that hold said blocks J, and as said timbers are firmly bolted together, as shown, the power of the 70 screws cannot separate the sections, and said blocks may continue to hold the screws until it becomes necessary to shift the blocks forward nearer the moving building, and by providing the sections of the ways with openings 75 j'', the blocks can readily be changed forward as often as occasion requires. So, also, as each section of the ways is relieved from the weight of the building and the presence of the anchor-block, it can be taken forward and connected again. These operations are repeated 80 until the work is done.

Where it is necessary, in order to secure the requisite power, to locate two screws together at each point where power is applied by the 85 use of the double-ended screw described, in reverse positions, each of the men operating them is enabled to do the work by moving his lever toward him and downward, instead of lifting thereon, thereby greatly relieving the labor 90 of one of the men and equalizing the burden between them. They are also enabled to maintain the same relative position from the beginning to the end of the work, which is an advantage. Putting the screw between two 95 barrel-timbers, instead of at the end of a single timber, brings the screw often in a more convenient position for the operator, and the double-ended feature permits the device to be used either end forward with equal facility. 100

The use of two oppositely-inclined threads permits an increase of speed without change of the pitch of the threads. The anchor-block, being unattached otherwise than by the strap, 5 accommodates itself to the angle of the screw-barrel, which is usually inclined. This is clearly shown in Fig. 3. Said anchor-block is readily shifted from point to point upon the runway by withdrawing the holding-pin, and it saves 10 the labor and damage attending the securing of anchorage in the pavement or ground. The movable rest L is sometimes employed to support the screw against the deflecting force of the actuating-lever. It is fashioned to fit the 15 boss and to allow the latter to rotate in it, and needs only to be placed in proper position without being attached in any way, being supported upon rollers l, which enable it to move with the boss as the latter changes position.

20 I claim—

1. In combination with the power-supplying screws and their anchorage devices, the continuous ways herein described, on which to slide or roll the buildings, formed of sections

of timbers secured together at their abutting ends by straps and bolts, substantially as specified.

2. The continuous ways herein described, composed of lengths of timber and fastenings for securing them detachably together end to end, substantially as specified.

3. The ways upon which to move buildings, in combination with the screws and their anchoring devices, the latter being secured directly to the timbers forming the ways, substantially as specified.

4. The combination, with the way and the power-supplying screws, of the anchor device consisting of the block, the strap, and the holding-pin, substantially as specified.

5. The combination, with the screw, of the supporting-rest L, substantially as specified.

Chicago, Illinois, September 18, A. D. 1883.

JAMES HOLLINGSWORTH.
